UNITED STATES PATENT OFFICE.

MORGAN M. ROTE, OF SUNBURY, PENNSYLVANIA, ASSIGNOR TO CHARLES J. REITZ, OF SUNBURY, PENNSYLVANIA.

HOT-AIR REGISTER.

Application filed April 5, 1928. Serial No. 287,610.

The invention relates to hot air registers for hot air heating systems and has for its object the provision of an improved construction of register that is reasonable in cost of manufacture and extremely durable.

A further object of the invention is the provision of a hot air register in which the casing is made of a single blank of sheet metal bent to provide a holding frame for a 10 grating and having an integral flange at right angles to the frame to engage in the end of the hot air flue of the furnace.

The invention will be described in detail hereinafter and will be found illustrated in 15 the accompanying drawings in which

Figure 1 is a top plan view of the improved hot air register,

Figure 2 is a transverse sectional view on a slightly larger scale than that shown in Figure 1,

Figure 3 is a fragmentary bottom plan view of one of the corners of the register structure, and

Figure 4 is a view of a blank from which 25 the casing for the register is constructed.

In the drawings similar reference characters are used to designate corresponding parts throughout the several views.

Referring to the drawings the casing of the 30 register is designated 1, and holds a grating 2. In Figure 4 is shown a sheet metal blank from which the casing 1 is formed, said blank being provided with an opening 3 in which

the grating 2 is mounted, the grating being held in position by bending the sides of the 35 blanks on lines designated 4 to form the frame that is U-shape in cross section as shown in Figure 2 and having a top portion 5 and a bottom portion 6 surrounding the opening 3, the end of the portions 6 being beveled or mitered as shown at 7 to form a miter joint when the parts are assembled as shown in drawings. The structure shown in the drawings is square in formation, and the beveled portion 7 is therefore formed at right angles 40 to lines describing diagonals of the opening 3. 8 indicates extensions on the sides of the blank having their side edges 9 on lines substantially parallel to the sides of the opening 3, said extensions being adapted to be bent 45 outwardly on lines indicated at 10 on planes substantially at right angles to the bottom portion 6 to form the flanges to engage the outer end of a hot air tube, (not shown). 50

What is claimed is:—

A casing for hot air registers for furnaces and the like, formed from a blank of sheet metal having a square opening therein, certain edges of said blank formed by cutting on lines forming right angles with continuations of diagonals of the opening aforesaid, and extensions on said blank at the ends of said edges on lines parallel with the sides of said opening.

In testimony whereof I affix my signature.
MORGAN M. ROTE.
